UNITED STATES PATENT OFFICE.

ALBERT H. EGSECKER, OF ST. LOUIS, MISSOURI, ASSIGNOR TO HEINE BOILER COMPANY, OF ST. LOUIS, MISSOURI, A CORPORATION OF MISSOURI.

WATER-TUBE BOILER.

Application filed December 31, 1924. Serial No. 759,009.

This invention relates to water tube boilers of the type that comprise banks of tubes that project upwardly from a lower drum, and has for its main object to provide a boiler 5 of the general class referred to which is equipped with a novel means for facilitating the removal of soot, dust and the like that collects on the top side of said lower drum.

Figure 1 of the drawings is a vertical 10 longitudinal sectional view of a boiler constructed in accordance with my invention.

Figure 2 is an enlarged transverse sectional view, taken on the line 2—2 of Figure 1, looking in the direction indicated by the 15 arrows; and

Figure 3 is a detail sectional view, taken on the line 3—3 of Figure 2 looking in the direction indicated by the arrows.

In the drawings A designates the lower 20 drum of a conventional vertical tube, bent tube boiler, B designates the rear tube bank, C designates a tube bank arranged in front of the rear bank and D designates a transversely-disposed baffle that is arranged between said tube banks. In order to facilitate the removal of soot and the like which collects on the top side of the lower drum A, the baffle D is provided at its lower end with one or more openings 1 through which soot 25 can be discharged from the top side of the lower drum by any suitable means, such, for example, as conventional soot blowers. The openings 1 are normally covered by closures that prevent the gases from short circuiting 30 from the pass in which the tube bank C is arranged into the pass in which the rear tube bank B is arranged, and when it becomes necessary or desirable to remove soot or the like that has collected on the top side 35 of the drum A, said closure or closures are opened so as to permit the soot to be discharged from the top side of the lower drum through the openings 1 in the lower portion of the baffle D. The form and specific location of the openings 1 are immaterial and any suitable type of closure may be used for said openings. I prefer, however, to equip the baffle D with two groups of openings 1 arranged in close proximity to the lower 40 drum A, and control each of said groups of openings by a closure equipped with an operating device that can be manipulated through an opening in the adjacent side wall of the boiler setting, that is normally closed 45 by a door. In the form of my invention

herein illustrated two slide valves E are used to form the closures above referred to, each of said valves being associated with one of the groups of openings 1 in the lower portion of the baffle D and being provided with an operating device 2 that can be manipulated through a hole in the adjacent side wall 3 of the boiler setting, that is normally closed by a door 3^a, as shown in Figure 2.

Instead of forming the entire baffle D 65 from fire brick or the like, I prefer to construct the lower part of said baffle from metal and construct the upper part of said baffle from fire brick, the clean-out openings 1 being formed in the metal lower part of 70 the baffle and the slide valves E being slidably mounted in or on said metal lower part. In the boiler herein shown the metal lower part of the baffle D is formed by a plurality of metal members F of substantially 75 channel shape in cross section arranged end to end longitudinally of the lower drum A and projecting upwardly from same so as to serve as a substantial supporting structure for the fire bricks that constitute the upper portion of the baffle D. The clean-out openings 1 are formed in the webs of the members F in close proximity to the bottom flanges 4 of said members and the slide valves E are supported by and slidably mounted on said flanges 4. Each of 80 said slide valves consists of a substantially oblong-shaped member provided with a web having openings 1^a that are spaced apart the same distance as the openings 1 which said 85 valve controls. When the boiler is in operation both of the valves E are arranged in the position shown at the left of Figure 2, wherein it will be noted that the imperforate portions of the web of the valve are arranged 90 over the openings 1 in the metallic lower portion of the baffle D. When it is desired to remove soot or the like from the top side of the lower drum A, the valves E are moved outwardly into the position shown at the 95 right of Figure 2, so as to bring the openings 1^a in said valves into registration with the clean-out openings 1 in the lower metallic portion of the baffle D, after which said soot can be discharged rearwardly 100 through the aligned openings 1 and 1^a in the baffle and in the valves E by soot blowers, or any other suitable means.

The metal members F that constitute the metallic lower portion of the baffle D are 110

preferably equipped with ribs 5 arranged above the clean-out holes in said members and integrally connected to the webs and to the top flanges of said members, and each of 5 the valves E is preferably provided adjacent its outer end with a lug 7 that cooperates with one of said ribs 5 to limit the movement of said valve in one direction, and a lug 8 that co-operates with said rib 10 to limit the outward movement of the valve during the operation of uncovering the clean-out openings 1, in the metallic lower portion of the baffle. As shown in Figure 1, the members F at the lower end of the baffle 15 D project upwardly and rearwardly from the lower drum A, and are arranged with their top and bottom flanges 6 and 4, respectively, projecting forwardly, the bottom course of fire bricks in the upper portion 20 of the baffle being supported by the top flanges 6 of said members, as shown in Figure 3. The valves E are not permanently connected to the members F, but are simply laid loose upon said members, this being 25 made possible by reason of the fact that members F are inclined rearwardly at such an angle that there is no possibility of the webs of the valves E moving out of contact with the webs of the members F.

30 Having thus described my invention, what I claim and desire to secure by Letters Patent is:

1. A water tube boiler provided with a lower drum, banks of tubes projecting upwardly from said drum, a transversely-disposed baffle between the rear tube bank and the tube bank in front of same that starts at said lower drum and projects upwardly from the same, an opening in the lower portion 40 of said baffle through which soot and the like can be removed from the top side of said lower drum, and a closure for said opening that is normally arranged over said opening so as to prevent the gases from 45 passing through the lower portion of the baffle.
2. A water tube boiler provided with a lower drum, banks of tubes projecting upwardly from said drum, a transversely-disposed baffle between the rear tube bank and the tube bank in front of same that starts at said lower drum and projects upwardly from the same, an opening in the lower portion 50 of said baffle through which soot and the like can be removed from the top side of said lower drum, a closure for said opening that is normally arranged over said opening so as to prevent the gases from passing through the lower portion of the baffle, and an actuating device for said closure operable from the exterior of the boiler.
3. A water tube boiler provided with a lower drum, banks of tubes projecting upwardly from said drum, a transversely-disposed baffle arranged in front of the rear

tube bank with its lower edge contacting with said lower drum, clean-out openings formed in the lower portion of said baffle across the entire width of same so as to facilitate the removal of soot and the like 70 that collect on any portion of the top side of said lower drum, and a means operable from the exterior of the boiler that normally closes said openings.

4. A boiler, comprising a lower drum, two 75 banks of water tubes projecting upwardly from said lower drum, a baffle that starts at said lower drum and projects upwardly from same between said banks, openings in the lower portion of said baffle through 80 which soot and the like can be removed from the top side of said drum, and a slide valve arranged to normally close said openings and provided with openings that are adapted to be brought into registration with 85 the openings in said baffle when it is desired to clean off the top side of said drum.

5. A water tube boiler provided with a lower drum, a bank of water tubes projecting upwardly from said lower drum, a 90 transversely-disposed baffle at one side of said tube bank that starts at said drum and projects upwardly from the same, said baffle having an inclined lower portion that is equipped with openings through which soot 95 and the like can be discharged from the top side of said drum, and a closure for said openings slidably mounted on the inclined portion of said baffle and normally arranged over said openings.

6. A water tube boiler, comprising a lower drum, water tubes projecting upwardly from said lower drum, a transversely-disposed baffle extending lengthwise of said drum and provided with a metallic lower portion and a brick upper portion supported by said lower portion, said metallic lower portion being equipped with clean-out openings, and valves slidably mounted on the metallic lower portion of the baffle and normally arranged over said clean-out openings.

7. A water tube boiler provided with a lower drum, water tubes projecting upwardly from said lower drum, a transversely-disposed baffle provided with a lower portion 105 composed of a plurality of substantially channel-shaped members arranged end to end and having clean-out openings formed in their webs, and closures that are normally arranged over said openings so as to prevent the gases from passing through the lower portion of the baffle.

8. A water tube boiler provided with a lower drum, water tubes projecting upwardly from said lower drum, a transversely-disposed baffle provided with an inclined lower portion formed by a plurality of metal members equipped with clean-out openings and each having a bottom flange, and slide valves supported by the bottom flanges of 115 120 125 130

said members and adapted to be arranged so as to normally close said clean-out openings.

9. A water tube boiler, comprising a lower drum, water tubes projecting upwardly from said drum, a transversely-disposed baffle whose lower portion is formed by a number of substantially channel-shaped members arranged end to end longitudinally of said drum, clean-out openings in the webs of said members, and valves that normally close said openings slidably mounted on said members and equipped with openings that are adapted to be brought into registration with the openings in said members when it is desired to clean off the top side of said drum.
10. A water tube boiler, comprising a lower drum, water tubes projecting upwardly from said drum, a transversely-disposed baffle provided with a lower portion composed of a number of substantially channel-

shaped metal members arranged end to end longitudinally of the drum, clean-out openings in the webs of said members, ribs on 25 said members integrally connected to the webs and top flanges of said members and valves slidably mounted on the bottom flanges of said members and adapted to be normally arranged over said clean-out open- 30 ings.

11. A water tube boiler, comprising a lower drum, water tubes projecting upwardly from said lower drum, a transversely-disposed baffle comprising an upper portion 35 constructed of brick and a lower supporting portion for said upper portion composed of a number of metal members arranged end to end longitudinally of said drum, clean-out openings in said metal members, and closures operable from the exterior of the boiler and adapted to be normally arranged over said clean-out openings. 40

ALBERT H. EGGSIEKER.
